UNITED STATES PATENT OFFICE.

GEORGE JOHNSTON, OF SAN FRANCISCO, AND EDWIN G. SMITH, OF SACRAMENTO, CALIFORNIA.

GRAPE STEMMER AND CRUSHER.

SPECIFICATION forming part of Letters Patent No. 327,693, dated October 6, 1885.

Application filed March 9, 1885. Serial No. 158,924. (No model.)

To all whom it may concern:

Be it known that we, GEORGE JOHNSTON, of the city and county of San Francisco, and EDWIN G. SMITH, of Sacramento, Sacramento county, State of California, have invented an Improvement in Grape Stemmers and Crushers; and we hereby declare the following to be a full, clear, and exact description of the same.

Our invention relates to an apparatus for stemming and crushing grapes.

It consists of an approximately horizontal case, in one end of which the bunches of grapes are delivered, a series of revolving arms or beaters fixed upon a shaft which extends through the case, and a series of angular adjustable or stationary spirals or guides fixed within the case, by which the stems are caused to pass out at the opposite end of the case after being separated from the grapes, a chute through which the separated grapes are delivered to the peculiarly-constructed rollers, and an inclined revolving and perforated drum or cylinder, within which the pulp and juice are finally separated.

Referring to the accompanying drawings for a more complete explanation of our invention, Figure 1 is a longitudinal vertical section taken through the axis of the casing. Fig. 2 is a transverse section showing the relative arrangements of the casing and rollers and the adjustment of the separating-spirals. Fig. 3 is a top view.

A is a casing, of suitable length and diameter, mounted preferably in a nearly or quite horizontal position. Through this casing a shaft, B, extends, having blades or beaters C extending outward from it nearly to the circumference of the lower part of the casing, which may be semi-cylindrical. One end of this shaft has a pulley or other suitable means by which it may be driven from any convenient source of power. The upper part of the casing A need not be cylindrical, the upper portion of it being at a greater distance from the central shaft than the lower portion. Within this upper portion are fixed guides or strips E, the outer edges of which fit the interior of the casing, while the inner curves approach closely to the edges of the beaters or blades, which are fixed to the central shaft. These guides or plates are fixed at an angle within the casing, so as to form par-

tially spiral guides by which the stems which are separated from the grapes are gradually forced along the casing until they are discharged at the opposite end. One end of each of these guides is secured by a screw passing through the hole in the outside of the casing, and the other end has a similar screw passing through a longitudinal slot in the other side of the casing by which this end may be moved so that the angle or spiral formed by the guides will be greater or less, as may be desired.

At one end of the casing is a hopper, F, into which the bunches of grapes are delivered, and as they pass into the casing the blades or beaters will separate the grapes from the stems. The grapes will fall down through a suitable opening in the lower part of the casing, while the stems are gradually advanced through the case until they fall out at the opposite end. The grapes fall through a guide-chute, G, upon two corrugated rollers, H, which are mounted horizontally upon shafts, so as to rotate side by side, with their corrugated faces interlocking or moving together, so that the grapes which pass between them will be thoroughly crushed. The meeting faces of these rollers are covered with rubber or other similar elastic material, which extends entirely around them, and the depressions or concavities of each roller have a metal plate, I, formed with the same curve and secured in the concavities, so as to hold the rubber in its place and prevent its slipping or moving upon the roller, at the same time the raised portion of the opposite roller, being covered with rubber to fit into the depression, which is metal lined, will be sufficiently elastic to prevent the crushing of the seeds which may pass between the rollers. After passing through the rollers the juice and pulp are discharged into a hopper or chute, J, from which they are delivered into an inclined cylinder, K, which is perforated with holes, so that the juice may fall through into a receptacle beneath, while the skins and pulp are gradually advanced through the cylinder by reason of its inclination until they fall out of the opposite end of the cylinder in a nearly dry condition.

By this construction the work of stemming the grapes, reducing them to a pulp, and separating the juice from the skins and pulp with-

out allowing it to remain too long upon them is effected rapidly, and with a very small amount of labor.

Having thus described our invention, what we claim as new, and desire to secure by Letters Patent, is—

1. In a grape stemming and crushing apparatus, a horizontal casing with revolving arms or blades within it, in combination with the stationary spirally-arranged guides, substantially as herein described.

2. In a grape crusher and stemmer, a horizontal casing with the arms or blades revolving within it, the spirally-arranged guides secured in the upper portion, and the screws passing through slots in the casing, whereby the angle of the spirals may be regulated, substantially as herein described.

3. In combination with the horizontal casing with its separating blades and guides, the directing chute or hopper into which the

grapes fall from the casing and the corrugated rotating rollers between which they pass, substantially as herein described.

4. The corrugated crushing-rollers having the exterior perforated cover of elastic material, in combination with concave metallic plates fixed in the depression of each roller, substantially as herein described.

5. In a grape-crushing apparatus, the stemming and crushing mechanism, as herein shown, in combination with an inclined perforated rotating cylinder and a chute by which the pulp is delivered into the said cylinder, substantially as herein described.

In witness whereof we have hereunto set our hands.

GEORGE JOHNSTON.
EDWIN G. SMITH.
